BRACE FOR A SPECTACLE TEMPLE OR
SIMILAR ARTICLE

Harry Weissman, New Hyde Park, N. Y.

Application May 23, 1951, Serial No. 15,285

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Brace for a Spectacle Temple or Similar Article, of which the following is a specification, reference being had to the accompanying drawing, forming a part hereof.

Fig. 1 is a perspective view of a brace for a spectacle temple or similar article, showing my new design.

Fig. 2 is a top plan view thereof.

Fig. 3 is a side elevational view thereof.

Fig. 4 is a vertical sectional view thereof taken on the line 4—4 of Fig. 3.

The essential features of my design are shown in full lines, the broken line showings being for illustrative purposes only.

I claim:

The ornamental design for a brace for a spectacle temple or similar article, substantially as shown and described.

HARRY WEISSMAN.
